UNITED STATES PATENT OFFICE.

ALVIN C. SLAUGHTER AND GEORGE DUNFORD, OF OKLAHOMA CITY, OKLAHOMA.

VISOR.

Application filed October 28, 1924. Serial No. 746,333.

To all whom it may concern:

Be it known that we, ALVIN C. SLAUGHTER and GEORGE DUNFORD, citizens of the United States, residing at Oklahoma City, 5 in the county of Oklahoma and State of Oklahoma, have invented a certain new and useful Invention in Visors, of which the following is a specification, reference being had to the accompanying drawings.

10 This invention relates to an especially scientifically constructed and arranged eye-shade or visor, the construction and arrangement involving the clearing of the device of the usual and well known objections 15 made to these matters.

It is an object of the invention to properly dispose and project a visor from the forehead, just above the eyes; to provide a fore-head band integral with or associated 20 with the same and to provide in that band a dual-ventilating system, and to associate, in combination with these features a head-band or strap system co-operative with the aforesaid features for the purpose of properly 25 positioning and holding the device about and to the head, which is an essential when vision, and protection of vision are combinedly considered.

Other objects of the invention will be 30 better understood by a careful reading of the following specification, drawing, and the appended claims.

On the sheet of drawings, accompanying 35 and forming a part of the said specification, Figure 1 represents a visor, in section, and partly broken away to show details of construction,

Figure 2 is a detail fragment showing 40 a means upon the upper edge of the fore-head band for ventilation;

Figure 3 is a detail fragment of perforation for roll either of Figure 1 or 4, and

Figure 4 is a view in section showing a 45 means of manufacture, where the band and the visor are in two parts and assembled.

In these views, similar characters of reference indicate similar parts.

The devices of Figures 1 and 2 are similar 50 except for the formation at the top of the fore-head band, and consist of a fore-head band 5, integral with which and proceeding therefrom at 6 is an eye shade or visor 7, the rear of the roll 6 constituting a forehead seat or base to take the natural 55 curvature of the line of the forehead. The

band 5, as will be seen from the diagrammatization in Figure 1 is at an angular relation to the perpendicular of the head-straps 8 and 9 respectively, so that when these straps are in proper place upon the head, the strap 9 taking a substantially horizontal position, and the strap 8 taking a substantially vertical position, the band 5 will flare from the fore-head, leaving a cooling space between it and the forehead, 60 and the rolled edge 10 of the band will form a circulating channel for cooling the radiation coming from the forehead.

In Figure 3, if desired, this roll 10 may be perforated, as at 11, for the purpose of 70 additional ventilation of the roll, as well as the ventilation out from the ends of the roll at each side of the fore-head band.

Referring again to Figure 1, near the extremities of the fore-head band 5 are openings through which are passed large tubular rivets 13 for the purpose of movably securing the head bands 8 and 9 to the fore head band 5, and for permitting movement of the parts adjustable to the natural movement of the head, as well as permitting the necessary adjustment of the bands to the shape of the head, and allowing the fore head band 5 to maintain its flaring position from the forehead, as aforementioned.

Referring to Figure 2, in lieu of the roll 10 at the upper edge of the fore-head band 5, the formation is as at 14 where the upper edge of the band 5 is simply corrugated.

It will now be seen that there is provided 90 a device as substantially set forth, including in combination independently and relatively movable head bands swiveled to a fore-head band, which in position flares from the forehead, for ventilating purposes, the upper end or edge of which band is provided with a sub-ventilating roll or formation to take the radiation from the forehead and deliver it sidewise of the fore-head band and dissipate the same.

It will further be noticed that the bottom rolled turn from the visor to the upstanding band is the only part that touches the fore-head surface, and this being at a single point or line in that curvature, renders the device of easy use and ready ventilation making the heat-point of contact with the head practically nil.

It is, of course, to be understood that both 105 of the head bands 8 and 9 respectively, will 110

be adjustable for size, aside from their relativity of adjustment, and for this purpose buckles 15 and 16 are provided.

Having thus described this invention, we claim:

1. An eyeshade including a visor having a forehead band attached thereto, said forehead band having its upper edge of greater length than the lower edge which joins the visor, and adjustable head bands pivotally attached to the forehead band by fastening

means passing through the bands at the ends of all of said bands.

2. In combination with the structure set up in claim 1, a formation about the upper edge of the forehead band for aiding in the dissipation of heat from said band.

In testimony whereof we have signed our names.

ALVIN C. SLAUGHTER.
GEORGE DUNFORD.
